O. ASHTON, DEC'D.

H. ASHTON, EXECUTRIX.

WORK SUPPORT.

APPLICATION FILED OCT. 1, 1919.

1,435,194.

Patented Nov. 14, 1922.

UNITED STATES PATENT OFFICE.

ORRELL ASHTON, DECEASED, LATE OF SWAMPSMOTT, MASSACHUSETTS, BY HANNAH ASHTON, EXECUTRIX, OF WOLLASTON, MASSACHUSETTS, ASSIGNOR TO UNITED SHOE MACHINERY CORPORATION, OF PATERSON, NEW JERSEY, A CORPORATION OF NEW JERSEY.

WORK SUPPORT.

Application filed October 1, 1919. Serial No. 327,764.

To all whom it may concern:

Be it known that ORRELL ASHTON, late of Swampscott, in the county of Essex and State of Massachusetts, deceased, invented 5 certain Improvements in Work Supports, of which the following description, in connection with the accompanying drawings, is a specification, like reference characters on the drawings indicating like parts in the several figures.

This invention relates to work positioning means for use in the manufacture of boots and shoes, and more particularly to means for positioning lasted shoes for the operation 15 of various machines such, for example, as fastening inserting machines.

An object of the invention is to secure adequate freedom of movement of the shoe on its support in presenting the same to the 20 work operating instrumentality and to this end an important feature of the invention resides in an improved work supporting means which permits the shoe to be shifted laterally and also turned about an axis 25 passing through the work.

In a preferred form of the invention the work supporting means described is arranged to co-operate with an abutment freely tilttable in all directions and against which 30 the work is pressed in locating it for the operation of the selected work operating instrumentality. A marked advantage of such an arrangement is that the lasted shoe is properly retained on its support during 35 movements in various directions by means of the freely movable abutment which maintains its operative face constantly in contact with the shoe at whatever angle the latter assumes in relation to the work operating 40 instrumentality. Preferably the abutment is supported for adjustment vertically and also laterally by means entirely independent of the construction by which universal tipping movement of the abutment is secured.

45 This provides for adjusting the abutment so as to position it properly against the shoe.

In another aspect, the invention resides in an improved support for the toe portion of a lasted shoe so constructed and arranged 50 that the shoe may be turned and tipped and shifted in various directions during oper-

ations on the toe portion of the shoe as, for instance, during the insertion of fastenings around the toe as reinforcing securing means. In the improved support a toe rest is provided which is conveniently supported upon an extension of the horn of the fastening inserting machine through means providing for tipping movement of the toe rest on the horn. 55

A further object of the invention is to provide an improved support for a lasted shoe so arranged that the last pin is adjustable toward and from the toe rest portion of the support and is automatically locked in 60 adjusted position when the toe of the shoe is placed upon the toe rest.

These and other features of the invention including important details of construction, and combinations of parts, will be herein- 70 after more fully described and claimed.

In the drawings:

Figure 1 shows in side elevation a loose nailing machine, together with a work support embodying the present invention; 75

Fig. 2 is an enlarged view, partly sectional, illustrating the last pin support and toe rest;

Fig. 3 is a detail view of the toe clamping button, and the adjustable devices for supporting it; 80

Fig. 4 is a cross-section through the work support at right angles to Fig. 2.

In the illustrative construction, there is provided a loose nailing machine 4 of any 85 well-known type but preferably like that shown in the patent to Louis Goddu No. 490,624, granted January 24, 1893, said machine having the usual foot plate 6 and driver 8. A sleeve 10 receives telescopically 90 the horn post 12, herein shown as having its upper portion 14 formed spherical to enter a spherical socket in a block 16. This block supports the base 18 of the toe rest, a dovetail or other sliding joint being provided between the members 16 and 18 to permit longitudinal sliding movements of the toe rest upon its support. Preferably the horn extension 12 carries a rod 20, which is received within a vertical slot formed in a 100 downwardly extending guide 22, which is rigidly secured to the block 16. The pro-

vision of the ball and socket joint between the members 14 and 16, provides for tilting movements of the toe rest upon the horn extension, and these movements are confined to a direction which is longitudinal of the last supported upon the toe rest by the guiding members 20 and 22.

In the construction shown, the base member 18 is provided with a rearwardly inclined upper face having a recess therein, the recess being covered by a plate 24 having therein a transverse slot adapted to receive a pin or bolt 26, which is secured to the supporting plate 28 of the toe rest carrier 30, upon which is supported, in a forwardly inclined position, a block 32 of rubber or other yielding material to sustain the toe of the shoe being operated upon.

Secured to the toe rest carrier 30 is a supporting arm 34 having its upper end portion bent at an inclination to receive the pad 32 and having a substantially vertical portion 36 extending downwardly from the pad and a laterally inclined portion provided with a slot 38, the surface of the arm on each side of the slot being roughened or serrated, as shown. The slot 38 receives a bolt 40, which likewise extends through an aperture in a plate 42 carried by a housing 44, which supports the tubular casing 46 of an adjustable last pin 48. Preferably the housing slides upon the lower slotted portion of the arm 34 and is frictionally held thereto by a spiral spring 50 which surrounds the bolt 40, and is confined against the lower surface of the plate 42 by an adjusting nut 52. In the construction shown, the last pin 48 and its casing 46 are pivotally sustained upon the housing 44 by a pin 54, the last pin being thereby tiltable, and the usual spring may be employed for yieldingly holding the last pin in a forwardly inclined position. Secured to the pin 54 is an arm 56, to the outer end of which is pivoted a rod 58 arranged to carry a slidable locking member 60, for locking the last pin 48 in adjusted position on the supporting arm 34. Conveniently the locking member 60 passes through an aperture in plate 42 and has its upper surface provided with serrations frictionally to engage the serrated surface 62 of the arm 34. Surrounding the outer portion of the rod 58 is a spring 64 confined between two thimbles 66, slidable upon the rod, the outer one of these thimbles being confined by nut 68 threaded to the rod, and the inner thimble bearing against the outer face of the locking member 60.

The construction described provides for an automatic locking device for securing the last pin in adjusted position upon the arm. In order to accommodate lasts of different lengths, the last pin may be adjusted along the slotted portion of the arm until it is located at the correct distance from the pad

32, suitable for the last which is to be placed upon the support. When the last is located with its toe portion upon the pad 32 and the pin 48 is inserted in the usual pin socket, the last pin will be tilted rearwardly against the force of the spring 64, thereby raising the locking member 60 and causing it frictionally to engage the serrated surface 62 and lock the last pin in its adjusted position relatively to the toe pad 32.

The foot plate 6 of the machine is provided with an extension 70, connected to the foot plate by a sliding joint indicated at 72 which permits lateral movement of the extension. A stem 74 has threaded engagement with an inclined hole formed in the extension 70, and the lower portion of said stem is connected by a ball and socket joint 76 with a button 78, whose lower face is shaped to engage the bottom of the toe end portion of a shoe supported on the pad 32. A set screw 80 is threaded into an aperture which intersects the aperture receiving the stem 74 and said set screw serves to secure said stem in adjusted position as determined by variations in the characteristics of the work.

The ball and socket connection between the stem 74 and button 78 provides for a wabbling or universal movement of the button relatively to its stem, thereby permitting said button to adapt itself automatically to varying inclinations of sole bottoms. When the shoe is properly positioned upon the support it may be turned by the operator, and moved laterally as it is being turned, in order to guide it properly with reference to the driver 8, or other work operating instrumentality, as, for example, during the operation of inserting reinforcing fastenings around the toe portion of a shoe carried by the last. A very important feature of the invention resides in the provision for clamping the toe portion of the shoe to the toe rest by clamping members co-operatively engaging the shoe, and capable of lateral and of turning movements without disturbance or interference with the clamping operation.

Having thus described the invention, what is claimed as new and desired to be secured by Letters Patent of the United States is:—

1. In a device of the class described, a toe rest and supporting means therefor, said parts being constructed to permit relative lateral and turning movements during the performance of an operation upon a shoe supported thereby, in combination with a clamping member constructed to move with the toe rest during the described movements of the latter to co-operate therewith in holding the toe of a shoe during operations thereon.

2. In a device of the class described, a toe rest, a support therefor, and means con-

- necting said parts constructed to permit the toe rest to turn and to move laterally on said support during the performance of an operation upon a shoe supported thereby, 5 in combination with a clamping member constructed to move with the toe rest during the described movements of the latter to co-operate therewith in holding the toe of a shoe during operations thereon.
- 10 3. In a device of the class described, a rest arranged to sustain the toe end of a shoe, a support for the rest, means for connecting the rest and support for relative lateral and rotary movements of said parts, 15 and means to engage the shoe bottom for clamping the shoe against said rest, said clamping means and rest co-operating to hold the toe of the shoe during the described movements of the rest.
- 20 4. In a device of the class described, a toe rest, supporting means for said rest constructed for tipping movement about an axis transverse of the shoe, and means for connecting said parts for relative lateral 25 and rotary movements of said rest and supporting means, in combination with a button for engaging the sole of the toe portion of a shoe to hold it on the rest and so arranged as to move with the rest 30 during the described movements of the latter.
5. In a device of the class described, a horn post extension, a toe rest, a toe rest support mounted on the extension and connected to the toe rest by a ball joint, and 35 connecting means arranged to permit of relative rotary and lateral movements between said toe rest and its support.
6. In a device of the class described, a 40 horn, a toe rest support, means for connecting said support with the horn arranged to permit of longitudinal tilting and sliding movements of the support, and a toe rest on said support, in combination 45 with a button mounted for sliding and for universal tilting movement and arranged to engage the sole of the toe end of a shoe to hold the shoe on the rest during the described movements of the latter.
- 50 7. In a device of the class described, a horn, a toe rest support on the horn, ball and socket and longitudinally sliding joints between said horn and support, and a toe rest on said support.
- 55 8. In a device of the class described, shoe supporting means comprising a toe rest, a toe rest support, a shoe bottom clamp and its support, and connecting means for permitting relative rotary and lateral movements between said toe rest and said clamp and their supports.
- 60 9. In a shoe support, a toe rest, means for supporting said rest with capacity for free rotary turning and lateral movements, 65 and a device for engaging the sole face of a shoe to clamp it against said rest, said device being supported for lateral and for universal turning movements.
10. In a shoe support, a toe rest, supporting means permitting said rest to turn 70 and to move freely transversely of the shoe, and a clamp for holding the shoe on said rest constructed for lateral and for wobbling movements.
11. In a device of the class described, a 75 toe rest support, and a toe rest sustained for turning, and for longitudinal and transverse sliding movements on said support, in combination with a member co-operating with the toe rest for clamping the toe of a 80 shoe on the rest and maintaining it clamped during the described movements of the rest.
12. In a device of the class described, a toe rest, and means supporting said toe 85 rest and constructed to permit turning, longitudinal and transverse sliding, and longitudinal tilting movements of said rest, in combination with a button for clamping the toe of a shoe on the toe rest mounted 90 for universal tilting movement.
13. A shoe support having, in combination, a toe rest, means for supporting said rest constructed to permit turning and lateral movements, a button for engaging the 95 sole face of a shoe on said rest, a support for said button, and means to permit relative universal movements of said button and support.
14. A shoe support having, in combination, a toe rest, supporting means permitting turning and lateral movements of said rest, a button to engage the shoe bottom opposite said rest, a stem connected with said button by a ball and socket joint, and means 100 for adjustably supporting said stem.
15. A shoe support having, in combination, a toe rest, means supporting said rest with capacity for relative turning and lateral movements, means to permit longitudinal 110 tilting movements of said rest, a button to engage the sole face at the forepart of a shoe on said rest, and a stem adjustable in its support and having a ball and socket connection with said button.
16. A shoe support having, in combination, a toe rest, a last pin, means permitting relative longitudinal adjustment of said parts, and means for automatically locking said parts in adjusted position when a shoe 120 is placed on said support.
17. A shoe support having, in combination, a toe rest, a last pin supported from said rest, means permitting relative adjustment of said rest and pin longitudinally of the shoe, and means for automatically locking said parts in adjusted position when the toe of the shoe is placed upon said rest.
18. A shoe support comprising a toe rest, a member extending from said rest, a tilt- 130

ing last pin slidably sustained on said member, and a lock for holding said pin to said member operated by the backward tilting of said pin when a shoe is placed on said support.

19. A shoe support comprising a toe rest, a slotted member extending from said rest, a last pin carrier having a spring-pressed pin movable in said slot, a tilting last pin supported on said carrier, and yielding locking means having connection with said pin and arranged to be moved into locking engagement with said member as said pin is tilted

rearwardly when a last is placed on the support.

20. A shoe support comprising a toe rest, a member extending therefrom, a last pin carrier adjustable on said member, a last pin, and a yielding lock connected with said pin and constructed to lock said carrier to said member when a last is placed on the support.

In testimony whereof I have signed my name to this specification.

HANNAH ASHTON,
Executrix of the will of Orrell Ashton.
